UNITED STATES PATENT OFFICE.

CHARLES E. SCRIBNER, OF JERICHO, VERMONT, ASSIGNOR TO WESTERN ELECTRIC COMPANY, OF CHICAGO, ILLINOIS, A CORPORATION OF ILLINOIS.

LOCK.

No. 851,900.

Specification of Letters Patent.

Patented April 30, 1907.

Application filed December 7, 1904. Serial No. 235,839.

To all whom it may concern:

Be it known that I, CHARLES E. SCRIBNER, a citizen of the United States, residing at Jericho, in the county of Chittenden and State of Vermont, have invented a certain new and useful Improvement in Locks, of which the following is a full, clear, concise, and exact description.

My invention relates to a lock for the door or cover of a box or other structure, and has for its object to provide improved means for preventing the door of the structure from being inadvertently left unlocked.

The main feature of the invention consists in the construction of the lock whereby an inserted key after operating the lock to permit the opening of the door of the structure cannot be removed until the lock is reversely operated and the door again closed and fastened thereby, so that a person after opening the structure cannot inadvertently remove the key and neglect to lock the box.

My invention contemplates a lock comprising two members, a latch and a keeper adapted to be locked in engagement under the control of a key, together with means, actuated upon the separation of said members for preventing the removal of the key from the lock. I also provide means, actuated upon the interlocking of said members for releasing the key to permit its removal. The lock may be applied to any desired structure, such as a box, drawer, or the like, and said members serve when in engagement to lock the structure against opening, but when said members are separated and the structure opened, the key will be held against removal until the said members are again in engagement to prevent access to the structure.

In the preferred form of my invention, the lock comprises a pivoted latch bar in a suitable frame secured to a wall of the box or structure, and adapted to engage a keeper upon the door or cover to lock the same. An opening is provided of the proper size to admit a key to the frame, the key bit engaging a portion of the latch bar to move the same out of engagement with the keeper, and when the bar is in such position another portion of the latch bar serves to prevent the return of the key bit to its original position where it could be removed. A blocking bar

is movably mounted within the frame, and means, actuated in the opening of the door, are provided, adapted to move said bar into a position to prevent the return movement of the latch bar, locking the same in its open position, and so holding the key against removal. The door of the structure is adapted in closing to effect the movement of the blocking bar to its former or normal position to permit the latch bar to be moved into engagement with said keeper to again lock the door and permit the removal of the key.

The latch bar may be arranged to be automatically moved, when the door is closed to withdraw the blocking bar, back to its position of engagement with the keeper to lock the door, and I preferably provide a spring for this purpose, which bears against the latch bar and operates to lock the same upon the withdrawal of the blocking bar.

I will describe my invention particularly by reference to the accompanying drawings, wherein

Figure 1 is a perspective view of a box equipped with the lock of my invention, the wall of the box being broken away to show the mechanism of the lock; Fig. 2 is a front elevation of the lock; Fig. 3 is a similar view with the face plate removed and showing the latch bar locked in its open position; Fig. 4 is a view of the lock showing the latch bar in its closed position in engagement with its keeper; Fig. 5 is a side view of the lock showing the same in position in the side of a box; Fig. 6 is a sectional view thereof on line 6—6 of Fig. 5; and Fig. 7 is a view of a key adapted for use in the lock of my invention.

The same letters of reference are used to designate the same parts in the several figures of the drawings.

Referring to Fig. 1, I have shown the lock of my invention applied to a box A. The frame *a* of the lock, which may be box-shaped, is secured to one of the walls of the box A, preferably on the inner side thereof. Within the frame is provided the latch bar or member *b*, preferably pivoted thereto, and projecting through an opening in the side of the frame. The latch bar is adapted when in the position shown in Fig. 4 to engage a keeper *c* carried by the door or cover *a'* of the box. The latch bar *b* is provided with two portions or projections *b'* *b''* between which

the bit of an inserted key K is adapted to enter to move the latch bar when the key is rotated, an opening being provided in the wall of the box and the face plate a^2 of the frame 5 to permit the entry of a key. These projections may form in effect an arm d for the latch bar having a recess d' therein which the key bit enters. Thus when the bit is moved to force the latch bar out of engagement with 10 its keeper the rear wall of the recess or the portion b' prevents the return movement of the key and its removal from the lock until the latch bar is returned to its locked position.

15 I accordingly provide a blocking device or movable blocking bar e with means actuated in opening the door for moving the bar into a position to prevent the return of the latch bar to its normal position. The door is also 20 arranged in closing to return the blocking bar to its former position and permit the latch bar to be moved into engagement with the keeper and allow the key to be removed.

25 The blocking bar e, which is preferably slidably mounted in the frame, may carry a lug e', and a spring f is adapted when the latch bar is moved to its open position and the door of the box is opened, to move the bar e into a position such that the lug e' registers with the end of the arm d and locks the latch bar in its raised or open position.

30 I provide means for stopping the blocking bar when the lug e' reaches the proper point to register with the arm d which means may consist of a pin g mounted upon the blocking bar near the end and adapted to engage the side wall of the frame a.

35 The side wall is provided with an opening at the end of the blocking bar, and the door 40 of the case is adapted in closing to engage the end of the bar to move the same to its former or normal position, moving the lug e' away from the arm d and allowing the latch bar to be moved to its locked position. The door 45 preferably carries a pin h, which, when the door is closed, engages the end of said blocking bar to effect the return movement thereof. This pin may, as in the present instance, be mounted directly upon the keeper c.

50 A spring i bears against the latch bar, and is adapted when the lug e' is withdrawn from engagement with the end of the arm d to move the latch bar into engagement with the keeper c. It will thus be seen that upon closing the door the same will be automatically 55 locked.

55 A stud k may be carried by the frame a to enter the hollow stem of an inserted key and serve as a support therefor, and one or more 60 segmental guides l may be provided as desired, adapted to ride in the slot or slots of a key bit, this guide serving to guard against the insertion of improper keys.

65 A stop m is carried by the frame adapted to prevent the rotation of the key in the

wrong direction and the consequent operation of the latch bar and the removal of the key.

By virtue of the construction above described, I am enabled to make a lock which 70 is simple, cheap and very effective and reliable in operation. The key after moving the latch bar into the open position, is positively locked in position against removal until the latch bar is returned to its locked position, as when the door is closed, so that the key cannot, through inadvertence, be removed while the door of the structure is unlocked. The door when closed is also automatically locked. 80

I claim:—

1. A lock comprising a pivoted latch bar, a keeper adapted to engage the same, an arm carried by said latch bar having a portion adapted to be engaged by a key bit to move 85 the latch bar out of engagement with said keeper, another portion of said arm preventing the removal of said key while the latch bar is in such position, means for locking the bar in its open position, and means for restoring 90 the latch bar into engagement with said keeper to release the key.

2. A lock comprising a pivoted latch bar, a keeper therefor, said latch bar being adapted to be operated by a key to control its engagement with said keeper, a spring-controlled longitudinally movable blocking bar released upon the separation of said latch bar and keeper to block the latch bar in its open position and prevent the removal of the 100 key, and means adapted to withdraw said blocking bar and permit the engagement of said latch bar and keeper, whereupon the key may be removed.

3. A lock for the door of a box or other 105 structure, comprising a frame secured to the wall of the structure, a pivoted latch bar within the frame, a keeper upon the door with which said bar engages to lock the same, an opening being provided for the insertion 110 of a key within the frame, the bit of the inserted key being adapted when the key is rotated to engage said bar and move the same out of engagement with said keeper, a blocking bar movably mounted within the frame, 115 means operative as the door is opened for moving said blocking bar to block said latch bar and key in the positions to which they have been moved, whereby an inserted key cannot be withdrawn while the door is unlocked, and means actuated in closing said door adapted to move said blocking bar to permit the return movement of said latch bar and the release of said key. 120

4. A lock comprising a pivoted latch bar, 125 a keeper adapted to co-operate therewith, a slideable blocking device operative upon the lifting of said latch bar from engagement with said keeper by a key, to block the latch bar in its raised position and prevent the 130

withdrawal of said key, and means actuated as said latch bar and keeper re-engage to withdraw said blocking device and permit the removal of said key.

5 5. A lock comprising a latch bar, a keeper adapted to engage the same, the engagement of said latch bar and keeper being controlled by a key, and a spring actuated slidable blocking bar operative upon the separation of said latch bar and keeper adapted to prevent the withdrawal of said key.

10 6. A lock for the door of a box or other structure, comprising a frame secured to a wall of the structure, a pivoted latch bar within the frame, a keeper upon the door with which said bar engages to lock the same, an opening being provided for the insertion of the key within the frame, an arm carried by said latch bar having a portion adapted 15 to be engaged by a key bit to move the latch bar out of engagement with said keeper, another portion of said arm preventing the removal of the key while the latch bar is in such position, a slide bar and a lug carried 20 thereby, a spring adapted upon the opening of said door to move said slide bar and bring said lug in engagement with said arm, means for limiting such movement of said bar, the door being arranged in closing to move said 25 slide bar to its normal position, whereby the latch when moved to open the door is blocked in position to prevent the removal of the key.

7. A lock for the door of a box or other structure, comprising a frame secured to an inner wall of the structure, a pivoted latch bar within the frame, a keeper carried by the door with which said bar engages to lock the door, an opening being provided through the 5 wall for the insertion of a key within the frame, an arm carried by said latch bar having a recess to receive the bit of a key, the bar being adapted to be moved by such bit out of engagement with the keeper, said key being adapted to be held by the bar, when in such position, against removal, a blocking bar slidably mounted in said frame, a lug carried by said bar, a spring adapted upon the opening of the door to move said slide 10 bar and bring said lug under said arm to lock the latch bar in its open position, a stud carried by said bar and engaging the frame when the bar is moved to limit the movement of said bar, a pin carried by the door adapted upon the closing thereof to return said bar to normal position, and a spring adapted upon the removal of said lug to

move the latch bar into engagement with said keeper.

8. A lock for the door of a box or other structure, comprising a frame secured to the wall of said structure, a pivoted latch bar within the frame, a keeper upon the door with which said bar engages to lock the door, an opening being provided for the insertion 60 of a key within the frame, a supporting stud carried by the frame adapted to enter the stem of such key, a segmental guide carried by the frame adapted to enter a slot in the bit of the key to guard against the insertion 65 of an improper key, said bar having portions between which the key bit is inserted, said bit when the key is rotated moving the latch bar out of engagement with said keeper, and being held between said portions against removal, a stop carried by the frame preventing the rotation of the key in the wrong direction, a blocking member movably mounted within the frame, means operated as the door is opened for moving said member to 70 block the latch bar in its open position, and means operated in closing said door for moving said blocking member to permit the return movement of the latch bar.

9. A lock for the door of a box or other 85 structure, comprising a frame secured to a wall of the structure, a pivoted latch bar within the frame, a keeper upon the door with which said bar engages to lock the same, an opening being provided for the insertion 90 of a key within the frame, a portion of the bar being adapted to be engaged by a key bit to move the latch bar away from said keeper, another portion of the latch bar being adapted to block the return movement of the key 95 bit in such position of the bar, mechanism operative upon the opening of the door of the structure adapted to block the latch bar in its open position, means operative upon the closing of the door for withdrawing said 100 mechanism, and means actuated upon the withdrawal of said mechanism adapted to move said latch bar into engagement with said keeper; whereby upon closing the door the same is automatically locked and the key 105 made removable.

In witness whereof, I hereunto subscribe my name this 12th day of September A. D., 1904.

CHARLES E. SCRIBNER.
